REGISTERING APPARATUS

Earl A. Keeler, Norristown, Pa., assignor to The Brown Instrument Company, Philadelphia, Pa., a corporation of Pennsylvania

Original application December 29, 1936, Serial No. 118,095. Divided and this application November 23, 1938, Serial No. 241,998

6 Claims. (Cl. 73—51)

This invention relates to the detection of broken filaments in a thread.

The present invention is a division of my prior application Serial No. 118,095, filed December 29, 1936 and issued into Patent 2,188,754 on January 30, 1940, and which discloses various arrangements for detecting broken filaments in a thread together with means actuated thereby for indicating and/or recording the number of such imperfections.

The various arrangements disclosed in my prior application were devised by me with the general object in view of providing simple and efficient means for detecting broken filaments in a single thread or in a plurality of threads together with means actuated thereby for indicating the presence and/or recording the number of such imperfections.

The apparatus claimed herein is an arrangement embodying my invention which is of especial utility in inspection operations where the actual number of thread imperfections is of minor importance and only an indication of the relative number of imperfections which pass the detecting means is desired.

In the manufacture of fabrics from rayon or other threads the presence of broken filaments in the individual threads shows up in the finished material in the form of fuzzy ends. Heretofore in order to eliminate these fuzzy ends provisions have been made for the inspection by observation of a portion of the thread during transfer of the thread from spool to spool and rejection of any spools having an excessive number of broken filaments. This inspection operation is obviously expensive and, more important from the standpoint of producing quality material, is inadequate by virtue of the fact that only a small portion of the total output can practicably be inspected.

Moreover, visual inspection of the thread during transfer of the thread from spool to spool and detection of broken filaments is difficult as will be readily appreciated when it is understood that rayon threads which themselves are extremely small in diameter are made up from 40 to 100 or more of such filaments. By means of the arrangement claimed herein, the manual inspection operation referred to may be dispensed with and broken thread filaments may automatically be detected and indicated by readily distinguishable means. As a means for such automatic detection, I employ a delicate switch member arranged in the path of the thread which is

actuated when engaged by the fuzz or broken filaments of the thread as the thread is transferred from one spool to another. Impacts of the moving fuzz projections on the delicate switch member, which has little inertia, result in the closure of a contact and thereby in energization of a suitable indicating means to be described. Thus an indication of the presence of broken filaments of the thread, which are difficult of detection by visual means alone, is had.

In some inspection operations for detecting defective thread filaments, it may be sufficient to record only the imperfections which pass the detecting means every minute or so to obtain a reliable record of the state of perfection thereof, the actual number of imperfections in the thread being of minor importance, and under such circumstances a material reduction in equipment may be effected. As one means for so detecting and recording the presence of defective filaments in the thread, I employ a detecting switch mechanism which is actuated by impact of broken filaments to close an energizing circuit for recording the thread imperfections and maintain this energizing circuit in such closed condition until auxiliary means have been energized for restoring the detecting means to its normal open position. Thus, a record of the thread imperfections may be had without the necessity of employing quick acting indicating instruments responsive to the closure of circuits which remain closed for only a period of short duration.

The various features of novelty which characterize my invention are pointed out with particularity in the claims annexed to and forming a part of this specification. For a better understanding of the invention, however, its advantages and specific objects attained with its use, reference should be had to the accompanying drawing and descriptive matter in which I have illustrated and described the best form of my invention now known to me.

Of the drawing:
Fig. 1 is a more or less diagrammatical view illustrating one form of the invention;

Fig. 2 is a perspective view of the detector of Fig. 1; and

Figs. 3 and 4 illustrate modifications of the Fig. 1 arrangement.

Referring to Fig. 1, provision is made, as illustrated, for arranging a detector 1 in the path of the moving thread for detecting the presence of broken filaments in the thread. Normally in practice, the detector may desirably be arranged

in the path of the thread as it is being unwound from a spindle on a spinning machine and wound on a bobbin immediately after the spinning operation. For clarity and definiteness of illustration, however, I have shown, in a more or less diagrammatic way, the thread 2 as being unwound from a spool 3 and reeled on a spool 4, the latter being mounted for rotation on a shaft 5 driven through suitable gearing, not shown, by a unidirectional electrical motor 6 energized for rotation from alternating current supply lines L¹ and L². The spool 3 is mounted for rotation on a shaft 7 which may be disposed on suitable brackets 8 in any convenient manner. Preferably both spools 3 and 4 are so mounted for rotation as to facilitate quick removal and replacement by other spools.

The detector 1 is a delicate switch mechanism including a contact arm 9 pivoted intermediate its ends for rotation on a light suspension wire 10, which may be of phosphor bronze or other suitable material, and disposed in the path of the thread. As best seen in Fig. 2, wire 10 is suspended between opposite arms of a U-shaped member 11 at the upper ends thereof. The arm 9 is provided at its upper end with a bifurcated portion or stirrup 12 which is so arranged that one arm of the stirrup is disposed on either side of the thread. The arms of stirrup 12 are separated by a distance slightly greater than the normal diameter of the thread so that any projecting portions of the latter resulting from broken filaments will engage one or the other or both of said arms. The arm 9, normally maintained in the position of Fig. 1 by means of a weight attached to the other end thereof, is adapted when engaged by broken filaments to engage a relatively fixed contact element 14 disposed at right angles to the arm 9 and securely fastened at one end to a stationary rod member 15 which may be mounted in any convenient manner as for example on the rod 16.

When broken filaments strike the stirrup 12 and rotate the arm 9 into engagement with the contact 14, the arm 9 is maintained in such closed relation with the contact 14 by a magnetic vane 17 which vane is rigid with the arm 9 and whose ends are disposed in inductive relation with the poles of a U-shaped normally deenergized electromagnet 18. When defective filaments actuate the contacting arm 9, one end of the vane 17 engages a leg 18' of the electromagnet 18 and residual magnetism in the vane 17 holds the latter in engagement with the leg 18' to thereby maintain the contacting arm 9 in engagement with the contact 14.

As illustrated, the engagement of contact arm 9 with contact 14 closes a circuit for energizing a heating coil 19. The heating coil 19 is disposed on a bimetallic strip 20 which in turn is mounted at one end on an insulated bracket 21 and has a pin 22 disposed on the other end which is adapted to engage one end of a spring marker arm 23. The spring marker arm 23 is mounted at its other end on an insulated bracket 24 and is adapted, when engaged by the pin 22, to have a marking pin 25 disposed on its movable end pressed into engagement with a ribbon 26 and a chart 27 for recording each such engagement. The recorder chart is adapted to be driven by a continuously rotating roller 27', the latter being driven in any convenient manner, as for example, by a unidirectional electrical motor (not shown) so that any imperfections of the thread will be recorded

on the chart as a series of contiguous marks on a straight line.

The heating coil 19 is energized from alternating current supply conductors L¹ and L² through a circuit which may be traced from the supply conductor L¹, conductor 28, heating coil 19, contacting arm 9, contact 14, and conductor 29 to the supply conductor L². Subsequent warping of the bi-metallic strip 20, caused by the heating of coil 19, presses the pin 22 into engagement with the spring marker 23 to thereby cause a record to be made of the closure of contacts 9 and 14, and to close an energizing circuit from the supply lines L¹ and L² to the electromagnet 18 for separating the contacts 9 and 14. When the relay 18 is energized, it attracts both ends of the vane 17 equally and causes the contacting arm 9 to move out of engagement with the contact 14 to a normal open circuit position. The resulting deenergization of the heating coil 19 permits the bimetallic strip 20 to cool, and subsequent return movement of the latter to its normal position as shown, breaks the contact between the spring marker arm 23 and the bimetallic strip 20 to deenergize the electromagnet 18.

In Fig. 3, I have illustrated an alternative form of switch contacting mechanism which may be employed in conjunction with the recording means of Fig. 1. As shown in Fig. 3, a delicately balanced mercury switch 30, comprising an elongated envelope having a pair of contacts 31 disposed in one end, is pivoted for rotation on a metal suspension wire 32 which desirably is a torsionless suspension. A contacting arm which may be similar to the contacting arm 9 of Fig. 2, is mounted on the elongated envelope of switch 30 by means of a light metal band 33, as shown, and upon impact of defective filaments with the stirrup 12, is adapted to overbalance the mercury switch 30, tilting the latter in a counter-clockwise direction to close the contacts 31. The mercury switch 30 remains in this tilted position due to the weight of the mercury 34, until a solenoid 35 is subsequently energized to restore the mercury switch 30 to its normal open position. The manner in which the solenoid 35 is energized may be similar to the manner in which the electromagnet 18 of Fig. 1 is energized. The solenoid 35 is adapted to cooperate with a magnetic vane 36 rigid with an arm 9' which is connected to the metal band 33 at a point diametrically opposite the point of connection of the contacting arm 9 thereto, so that, when the solenoid 35 is energized, the vane 36 is attracted and causes rotation of the mercury switch 30, restoring the latter to its normal balanced position to thereby open the energizing circuit to the heating coil 19 at the contacts 31.

In Figs. 1 and 3 inertia of the heating coils 19 and/or the bimetallic strips 20 causes the marking pins 25 to remain momentarily in contact with the ribbon 26 and chart 27 after the heating coils 19 are deenergized so that the thread imperfection is recorded as a short line. If successive defective filaments engage the stirrups 12 immediately thereafter, the heating coils 19 will be further energized and cause the marking pins 25 to remain in engagement with the ribbon 26 and chart 27 for a longer period of time to thereby record the passage of the additional number 70 of thread imperfections by a longer line.

In Fig. 4 I have shown another modification of Fig. 1 in which a solenoid 37 connected in circuit with the mercury switch contacts 31 is adapted to actuate a marker lever 38 pivoted at 75

one end on a shaft 39. A print hammer 40, disposed on the other end of member 38, is adapted to strike the recorder chart 27 through the ribbon 26, and thereby to make a mark on the recorder chart each time that the relay winding 31 is energized. The member 38 is normally biased for rotation in a clockwise direction by spring means 41 into engagement with a stop 42 so that when the solenoid 37 is deenergized the print hammer 10 40 is held out of engagement with the recorder chart 27 and ribbon 26.

As illustrated in Fig. 4, rotation of the delicately balanced switch mechanism 30 to its on position by impact of defective filaments on the 15 stirrup 12 results in the energization of the recording solenoid 37 and the restoring solenoid 35 which are series connected through the contacts 31 of the mercury switch 30 to the supply lines L¹ and L². For recording the presence of defective filaments and subsequently restoring the detecting mechanism to its normal position, the recording solenoid is adapted to actuate the lever 38 before the solenoid 35 responds to the energizing current and causes rotation of the mercury 20 switch 30 to its normal balanced position. Closing of the mercury switch contacts 31 thereby results in a mark being made on the chart 27 and immediately thereafter restoration of the mercury switch to its balanced open circuit position.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims, and that certain features of my invention may sometimes be used to advantage 40 without a corresponding use of other features.

Having now described my invention what I claim as new and desire to secure by Letters Patent is:

1. In apparatus for detecting defective filaments in a thread, a detector disposed in cooperative relation with said thread and having a normal condition and an actuated condition, means for relatively moving said thread and detector, said detector being adapted to be operated to its actuated condition by said defective filaments, and means continuously responsive to the actuation of said detector for recording the presence of said defective filaments and for restoring said detector to its normal condition.

2. In apparatus for detecting defective filaments in a thread, a delicately balanced detecting switch disposed in cooperative relation with the thread, means for relatively moving said thread

and detecting switch, means under control of said defective filaments for rotating said detecting switch to an unbalanced position, and means continuously responsive to rotation of said detecting switch for recording the presence of said defective filaments and for restoring the said detecting switch to its normal balanced position.

3. In apparatus for detecting defective filaments in a thread, detecting means disposed in the path of the thread, means for relatively moving said thread and detecting means, a heating coil, means under control of said detecting means for energizing said heating coil, and means responsive to said heating coil for recording said energization.

4. In apparatus for detecting defective filaments in a thread, a delicately balanced arm pivoted intermediate its ends for rotation and adapted to be engaged at one end and rotated by defective filaments in said thread, an electrical contact adapted to be engaged by said arm on rotation of the latter, a magnetic vane carried by said arm, means disposed in cooperative relation with said magnetic vane for maintaining the said electrical contact closed, and means energized by the engagement of said electrical contact and adapted to record such engagement and to operate the first mentioned means to open said electrical contact.

5. In apparatus for detecting defective filaments in a thread, a delicately balanced switch comprising a closed envelope supported for rotation, a pair of contacts disposed in said envelope and adapted to be closed by an electrical conducting liquid in said envelope when the said switch is caused to be unbalanced, an arm rigid with said envelope having one end disposed in cooperative relation with said thread and adapted when engaged by defective filaments to rotate said envelope for closing said contacts, and means actuated by the closure of said contacts for recording such closure.

6. In apparatus for detecting defective filaments in a thread, a delicately balanced switch comprising a closed envelope supported for rotation, a pair of contacts disposed in said envelope adapted to be closed by an electrical conducting liquid in said envelope when the said switch is caused to be unbalanced, a light arm rigid with said envelope having one end disposed in cooperative relation with said thread and adapted when engaged by defective filaments to rotate said envelope for closing said contacts, and means actuated by the closure of said contacts for recording such closure and subsequently restoring said switch to its balanced condition.

EARL A. KEELER.
